UNITED STATES PATENT OFFICE.

WILLIAM FRIESE-GREENE, OF LONDON, ENGLAND, ASSIGNOR TO COLOUR PHOTOGRAPHY LIMITED, OF LONDON, ENGLAND.

COLOR PHOTOGRAPHY.

1,391,310.

Specification of Letters Patent. Patented Sept. 20, 1921.

Original application filed July 8, 1919, Serial No. 309,455. Divided and this application filed January 31, 1921. Serial No. 441,495.

To all whom it may concern:

Be it known that I, WILLIAM FRIESE-GREENE, a subject of the King of England, residing in London, England, have invented 5 certain new and useful Improvements in Color Photography, of which the following is a specification.

This invention is for improvements in or relating to color photography, and has for 10 one of its objects to improve the production of colored photographs whether for use as transparencies or for mounting on opaque mounts. The invention is applicable both to the photography in colors of still life and 15 animate or inanimate objects and to cinematography, and renders such color photography more simple in operation.

Another part of the invention relates to an improved process of color photography 20 in which two sensitized surfaces are simultaneously or substantially simultaneously exposed the one through a color filter and the other without such filter.

A specific object of the invention is to improve color photography processes based 25 upon the employment of two colors whereby an approximation to natural color effects is obtained. In particular the invention aims at improving two-color cinematography. 30 These and other objects and features of the invention will now be described in detail, with the aid of the accompanying drawings, in which—

Figures 1 and 2 diagrammatically illustrate two arrangements of the sensitized surfaces upon which the original exposures are 35 made; and

Fig. 3 illustrates diagrammatically two superimposed surfaces bearing the resultant 40 photographic images.

The color sensitizer according to the present invention comprises pinacyanol, pinaverdol, pinachrome, flavazine (sometimes flavazin or flavasine) and ammonia 45 mixed with water, and preferably the proportions employed are as follows:—

Pinacyanol	2 grains
Pinaverdol	6 grains
Pinachrome	2 grains
Flavazine	4 grains
Ammonia (.880)	4 ozs.
Distilled water	65 pints

In making up the sensitizer the first four

ingredients in the quantities stated are preferably placed in 10 ozs. of boiling alcohol and stirred for say 10 minutes until thoroughly dissolved, after which 65 pints of distilled water may be added at a temperature of about 70° Fahr. and then the 4 ozs. 55 of ammonia added. The film or plate to be color-sensitized is immersed in this mixture for about 5 minutes and kept constantly in movement. The drying should be effected quickly at a temperature of about 75° Fahr. 60

The light-sensitive surface of a photographic plate or film color-sensitized by this formula is panchromatic, and such plates or films may be used for any purpose for which panchromatic plates or films 70 are suitable, giving very efficient results and satisfactory color effects. According to the present invention, however, panchromatic plates or films color-sensitized by the above formula, are used in improving color-photography on the two-color principle. 75

The ingredients detailed above are referred to by the names commonly given to them in the chemical and color photographic industry. It will be understood, however, 80 that pinacyanol (sometimes known as sensitol red) is obtained by treating quinaldinium salts with formaldehyde followed by alkali.

Pinaverdol is p-toluquinaldinquinolinium- 85 methylcyaninbromid.

Pinachrome is p-thoxyquinaldin-p-methoxyquinoline-ethylcyaninebromid.

Flavazine is one of the few important dyes belonging to the small class of pyrazole 90 lone dye-stuffs and is a dye similar to tartrazin.

In the photographic process according to the present invention, the two superimposed light-sensitive surfaces 1 and 2, Fig. 1, are 95 supported by separate backings of glass or transparent films 3 and 4, respectively, as commonly employed in photographic processes or, as shown in Fig. 2, they are both supported on a single backing 5. The surface 1 which is to be nearer the lens than is the other is prepared in the manner of an ordinary non-color-sensitized emulsion. That surface which is farther away from the lens is a photographic emulsion sensitized by means of the sensitizing solution hereinbefore described so as to render it 100 panchromatic. The two surfaces are pref-

erably on separate backings placed face-to-face, as shown in Fig. 1, and are simultaneously exposed in the camera, the front surface 1, that is to say the one which is first 5 acted upon by the incident light being prepared from the ordinary non-color-sensitized photographic emulsion.

Alternatively both plates may be specially color-sensitized in the manner and by the 10 solution hereinbefore described. In either case, whether one only or both of the surfaces be specially sensitized the front surface acts as a color-filter for the second surface so that the resulting two negatives 15 represent different color values and this difference is made greater by the use of the special sensitizer above described than is possible with panchromatic sensitive surfaces such as have heretofore been known. 20 The front surface, whether specially sensitized or not, is acted upon by the incident light without the interposition of any color-screen or filter and, in the case of a non-specially-sensitized surface, will be particularly 25 affected by light from the blue end of the spectrum and only slightly or comparatively slightly by light from the red end of the spectrum. The red rays, however, together with some green and blue, will pass 30 through the front surface and will operate upon the rear surface which is specially sensitized as above described.

Color-images can then be produced from the two negatives thus obtained whether on 35 separate backings or on a single backing, either by toning or staining the negative images themselves or positive images obtained therefrom, or in any other suitable way. The colors preferably used are, say, 40 orange-pink or some other color toward the red end of the spectrum and blue-green or some other color toward the blue end of the spectrum. Whether the negatives themselves are being colored or whether an 45 opaque positive is in question, the negative image nearer the lens or the positive image produced from it, will be colored orange-pink and the other negative image or the corresponding positive image will be colored 50 blue-green.

Where two transparent positives are to be used together, for example for cinematograph films as pictures or transparencies viewed by transmitted light or as lantern 55 slides the positive image produced from the negative that was nearer the lens will be colored orange-pink and the other blue-green.

In either case the coloring may be effected in a toning bath or by staining applied to the negative or positive as the case may be. After coloring, the negatives, such as 6 and 7, Fig. 3, or positives are mounted in register on a single backing 8 or, in the 65 case of cinematograph films, they are suit-

able for simultaneous individual exposure to be superimposed in register on the screen onto which they are projected.

Any suitable means may be employed for toning or staining the two negatives or positives, the colors being adjusted to the color-effects desired in accordance with the subject under treatment.

The marked difference of color values obtained by the use of the special sensitizer 75 aforesaid, leaves room for considerable manipulation of the colors in the toning- or staining-bath, so that the depth of color of either plate may be modified as required to obtain a proper balance according to the 80 color effects desired and according to the subject under treatment. This balance can only be judged by the operator for each subject, and will depend largely upon individual taste, but the fact that a large difference of color value is obtained by means of 85 this invention leaves scope for the desired manipulation.

For quick work, the employment of two 90 panchromatic plates or films prepared with the special sensitizer aforesaid is preferred.

If one print is on paper and the other on a transparent material, the transparent print will be superimposed upon the opaque print 95 in register therewith in the relative positions indicated in Fig. 3, and the two may then be mounted in any desired manner. With practice a colored photographic print having considerable resemblance to nature 100 can thus be obtained.

Although plates, such as 3, 4 and 5, have been referred to, obviously films may be employed in their place, and also the finished product may be made as a transparency suitable say for cinematograph projection, by 105 utilizing transparent material for both prints.

In applying the invention to cinematography, the celluloid portion of the films 110 may be of ordinary manufacture but the sensitizing material for one or both of the films should preferably be made as aforesaid. The two films can be run simultaneously through the camera for exposure, as, for example, with the sensitized surfaces in contact as shown in Fig. 1, and the subsequent treatment will be the same as has already been described with reference to plates. The final product, however, will be a transparency, with the parts in the relative 115 positions of Fig. 3. Instead of toning the final product to different colors, the film may be stained the desired colors on opposite sides though, for the production of ordinary colored photographs the process as first 120 described may be used. For cinematograph work the staining is possible because of the persistency of vision and the strong light behind the film.

The present application is a division of 130

my application Serial No. 309,455, filed July 8, 1919.

What I claim as my invention and desire to secure by Letters Patent is:—

- 5 1. A color-photography process, comprising simultaneously exposing two superimposed sensitized surfaces whereof at least one is color-sensitized with pinacyanol, pinaverdol, pinachrome, flavazine and ammonia mixed with water.
- 10 2. A color-photography process comprising making a simultaneous exposure of two superimposed sensitized surfaces of which the one remote from the object is color-sensitized with pinacyanol, pinaverdol, pinachrome, flavazine and ammonia mixed with water.
- 15 3. A color-photography process comprising simultaneously exposing without a light filter or other color-screen two superimposed sensitized surfaces of which the one nearer to the incident light is an ordinary non-color sensitized emulsion and the other is color-sensitized with pinacyanol, pinaverdol, pinachrome, flavazine and ammonia mixed with water.
- 20 4. A color-photography process comprising simultaneously exposing without a light filter or other color-screen two superimposed sensitized surfaces placed face - to - face of which the one nearer the incident light is an ordinary non-color sensitized surface and the other is a panchromatic sensitized surface.

In testimony whereof I affix my signature. 35
WILLIAM FRIESE-GREENE.
